UNITED STATES PATENT OFFICE

172,115

MOTOR VEHICLE CAB

Herbert W. Templeton, Fairmont, Minn., assignor
to Fairmont Railway Motors, Incorporated,
Fairmont, Minn., a corporation of Minnesota

Application November 12, 1953, Serial No. 27,571

Term of patent 14 years

(Cl. D14—3)

To all whom it may concern:

Be it known that I, Herbert W. Templeton, a citizen of the United States and a resident of Fairmont, county of Martin, and State of Minnesota, have invented a new, original, and ornamental Design for a Motor Vehicle Cab, of which the following is a specification, reference being had to the accompanying drawing, forming a part thereof, in which

Fig. 1 is a front perspective view of a motor vehicle cab, showing my new design;

Fig. 2 is a front elevation thereof, and

Fig. 3 is a side elevation thereof.

The essential features of the design reside in the portion shown in full lines.

I claim:

The ornamental design for a motor vehicle cab, substantially as shown and described.
